MACHINE FOR MAKING CIGARETTES HAVING FILTER OR LIKE PLUG OR OTHER MOUTHPIECES

Desmond Walter Molins, Deptford, London, England, assignor to Molins Machine Company Limited, Deptford, London, England, a British company

Application October 4, 1949, Serial No. 119,468
In Great Britain October 11, 1948

2 Claims. (Cl. 131—61)

1

This invention concerns improvements in or relating to machines for making cigarettes having filter or like plug or other mouthpieces of the kind in which alternate lengths of mouthpiece material, such as plug material, and tobacco filler are enclosed in a web of cigarette paper to form a continuous rod from which cigarettes provided with plugs or other mouthpieces are cut. Such machines will for convenience be referred to herein as "machines of the kind referred to."

Plugs are often made of crepe paper or like material, and some include absorbent material and are then known as filter plugs or sometimes as filter tips but for clearness all kinds of mouthpieces (including hollow tubes) intended to be enclosed with tobacco in a paper wrapper to form a mouthpiece cigarette will be termed hereafter "stubs."

It has been proposed to employ an intermittently rotating drum which has peripheral bores, into each of which in turn is inserted a stub by means of a reciprocating plunger or the like which thrusts a stub lengthwise into a bore when the latter is at an appropriate position. Each bore in turn having thus received a stub, is brought into line with a moving tobacco filler, and the stub and a portion of the tobacco filler are moved through and out of the bore end to end. The tobacco filler is severed to separate the section which remains in the bore from the rest of the filler, and the separated section is removed out of line with the filler by a rotary movement of the drum. The same rotary movement of the drum brings a further bore, containing a further stub, into line with the filler so that the stub can replace the removed tobacco section. The latter is ejected axially from the bore for example by means of a reciprocating plunger or by a fresh stub being inserted.

An object of the invention is to provide a machine of the kind referred to which can operate at a higher speed than existing machines.

According to the present invention there is provided apparatus for making cigarettes having mouthpieces wherein there is provided an intermittently rotatable drum which has a plurality of flutes on its periphery, means to insert a stub into a flute and means to feed a tobacco filler axially into and through a flute while the drum is stationary, the arrangement being such that on rotation of the drum a section of the filler contained in a flute is removed from the filler and is replaced on the next rotational step of the drum, by a stub carried by a succeeding flute.

2

It will be seen that with such a drum it is possible if desired to fill the flutes with stubs by a radial movement. In the specific description given later the stubs move axially towards the flutes but as the latter are wide and open the transfer can be effected much quicker than in the drums having bores as in the latter case the stubs cannot move until the drum is quite still. Thus this apparatus can work at much greater speed than earlier constructions. Moreover flutes can be cleaned easily to eliminate particles of tobacco which tend to gather round the stub and spoil the resulting mouthpiece cigarettes. Where special cleaning means are provided these can act non-reciprocally. For example, a brush (e. g. a rotatable brush) may be arranged to pass through a flute. It will also be appreciated that by suitably arranging the parts the tobacco in a flute can be caused to fall out of the flute by gravity at a desired time, any residue of tobacco in the flute being then removed by the cleaning means mentioned above or by centrifugal force in high-speed apparatus. Alternatively or in addition, the cleaning means may comprise an air blast directed against a flute.

When, as will usually be the case, the flute into which the tobacco filler passes when the drum is stationary is the one which is at the bottom of the drum, at that moment, means is provided for supporting the filler in position in the flute. Such means may comprise a narrow fixed support or a roller extending along the flute, so arranged as to allow loose particles of tobacco to fall out of the flutes.

Guide tubes may be provided, one on each side of the drum, to guide the tobacco filler into and out of a flute, the ends of the tubes being in rubbing contact with the sides of the drum so that an edge of a flute rubs against each tube end when the drum is rotated and provides a shearing action for the purpose of dividing from the tobacco filler the section to be removed therefrom. The drum may have insets of hard material at the flute edges to resist wear and improve the shearing action.

Any known means may be provided for supplying stubs or stub portions to the fluted drum but a preferred form is recited below.

50 There may be provided feeding apparatus comprising a hopper or the like for containing stock lengths of stub material, as hereinafter defined, means for feeding the lengths to a fluted wheel, cutters co-operating with the wheel to subdivide the lengths and a conveyor adapted to receive

the subdivided portions and transfer them to the flutes of the intermittently rotating drum.

A shield may be provided to cover the flutes of the wheel from the stock length receiving position to the delivery position and this shield may be stepped at the delivery end to control the subdivided portions. A further shield may be provided covering the drum flutes from the position where stub portions are received to the flute next to the tobacco filler.

The invention will now be described by way of example with reference to the accompanying drawings which show all the parts of the machine necessary for understanding how a filler is treated to remove sections thereof and replace them by stubs.

In the drawings:

Figure 1 is a front elevation of the apparatus and shows also a portion of the cigarette machine.

Figure 2 is a view of Figure 1 in the direction of the arrow A and partly in section.

Figure 3 is a plan of the apparatus shown in Figure 1 and partly in section.

Figure 4 is a view of a fragment of Figure 3 showing a shield in detail which is in section in that figure.

Figure 5 is a view of a fragment of Figure 3 showing the parts more clearly.

Figure 6 is a view of part of Figure 3 in the direction of the arrow B showing a few parts of the main drive.

Figure 7 is a view of a fragment of Figure 3 showing parts of the driving devices hidden in that figure.

Figure 8 is a view of a fragment of Figure 3 showing driving devices for the fluted drum, said devices being hidden in Figure 3.

Referring to the drawings, the machine, which closely resembles an ordinary continuous rod cigarette machine, is provided with a tobacco hopper 1 in which a shower of tobacco is caused to fall on an endless travelling band or tape 2 (hereafter referred to solely as a band) which forms the showered tobacco into a loose continuous tobacco filler. As the remaining part of the machine, to which the apparatus illustrated is fitted, is in all respects an ordinary continuous rod cigarette making machine further description of the hopper is unnecessary as those skilled in the art will readily understand the showering of tobacco and the forming of it into a filler, as such operations are fundamental to any continuous rod machine.

The showered tobacco is conveyed by the band 2 and formed into a filler and compressed by compression wheels 3 and 4 into a moderately compact mass and in that state is fed through a guide tube 5 which terminates flush with the side of an intermittently rotating drum 6 rotatable on a fixed axis 6A.

The thickness of the intermittently rotating drum 6 is approximately equal to the length of two stubs, as the usual practice in making cigarettes of this kind is to assemble alternate double lengths of tobacco filler and double-length stubs, enclose them in a paper wrapper and thereafter to cut the stub and tobacco portions midway to make two mouthpiece cigarettes. For clearness the double length stubs will be called hereafter "stub portions" and double lengths of tobacco filler will be called "filler portions".

The drum is provided with a number of flutes or grooves 7 on its periphery equally spaced and running parallel to its axis. The flutes are of the

well-known shape commonly employed on drums for feeding cigarettes and other rod-like articles, see Figure 2, and the lowest flute, whenever the drum is stationary is in alignment with the guide tube 5.

Stub portions are fed into successive flutes of the drum at the upper side thereof in a manner described in detail later and when the drum is stationary the leading end of the tobacco filler passes through the guide tube 5 and along the lowest flute until, when the leading end is beyond the far side of the drum by an amount equal to a filler portion, the drum moves round one stage (i. e. one flute pitch) during which movement the continuous filler is sheared as described later so that the section lying in the drum flute is separated and removed from the rest and the stub portion in the succeeding flute is brought into position to occupy the space vacated by the removed section. A shield 8 covers the flutes from the stub portion receiving position to the flute before the one through which the filler passes, to prevent stub portions from falling out of the flutes.

At a suitable position above the drum and associated devices described there is fixed a hopper 9 in which stock lengths of stub material are deposited. The stock lengths of material are sufficient to provide six finished stubs and during the process of feeding lengths out of the hopper they are cut by rotatable knives 10 into three pieces each of which pieces constitutes a stub portion. The feeding operation may be carried out in any known way, for example, in the way in which cigarettes are fed out of a hopper by the employment of a fluted wheel in the flutes of which the stock lengths of material successively fall. This is the method illustrated and as seen in Figure 1 the wheel, generally indicated by the reference 11, is formed by a series of four spaced fluted discs so as to provide spaces in which certain devices referred to later may work. The middle discs 12 are twice the width of the outer discs 13 and are peripherally grooved at 14 to accommodate the two circular knife blades 10 which rotate and divide the stock lengths into three equal stub portions. A shield 15 is provided around one side of the drum to cover the flutes and prevent stub portions from falling out of the flutes until they reach the bottom level of the wheel. The shield is stepped as shown in Figure 4, in any suitable manner to ensure that the three stub portions in a flute move out of it one after another. The three steps 16, 17, 18 shroud the wheel flutes so that the stub portions cut from one stock length fall into grooves 26 of a support 25 described later with reference to Figure 5 in alignment with pusher faces 28 and 29 and 30 shown therein. Moving fingers or pressers 19 are arranged within the spaces between the fluted discs 12 and 13 and operated by any suitable mechanism to ensure that the stub portions move out of the flutes at the proper time and under proper control. The mechanism shown comprises a cam lever 20 fixed to a shaft 21 to which the ends of the pressers 19 are also fixed. The upper end of the cam lever 20 has a roller 22 on it which is drawn into engagement with a crown cam 23 by a spring 24, see Figure 2. Thus as the cam 23 rotates, the operative ends of the pressers move up and down. The stub portions move down into a grooved support 25, Figure 5, whose grooves or channels 26 are in alignment with the three corresponding flutes 7 on the upper part of the

drum 6 whenever the latter is stationary and they therefore fall into the grooves or channels of the support in a similar arrangement. As will be gathered from the description of feeding and cutting the stock lengths, the stub portions in the channels 26 are spaced by different distances from the drum 6. It is therefore necessary to move the stub portions in said grooves by different amounts to feed them into the drum flutes and this operation is performed in the following way:

A reciprocating pusher 27 is provided for pushing stub portions lengthwise along the grooves of the support and into the flutes of the drum 6. The pusher is stepped as shown in Figure 5 so as to have three separate pusher faces 28, 29, and 30 each of which is arranged, on a forward stroke of the pusher, to engage the end of a stub portion. It will be seen from the above description and Figure 4 that the three stub portions which are transferred on to the support at each movement of the wheel are arranged on the support in staggered formation. The stepped pusher is arranged to move, on each forward stroke, a distance approximately equal to the length of a stub portion, and thus at each such stroke it moves each stub portion approximately one stub portion length forward. The stub portion nearest to the drum is thereby moved into a flute of the drum, while each of the other two stub portions is moved a stub portion length towards the drum 6. The movements of the various parts are so timed that whenever three stub portions are transferred in staggered formation on to the support, the pusher moves forward, and it will be seen that after the first three strokes, each stroke of the pusher will cause the three stub portions nearest to the drum to be moved endwise into three consecutive flutes of the drum.

The fluted wheel 11 by which the stub portions are conveyed moves one flute pitch for every three movements of the drum 6. Thus each time the pusher is operated there will be three empty drum flutes aligned with the grooves 26 of the stub portion support 25. It is therefore possible to convey and feed the stub portions at a relatively slow rate while at the same time the drum 6 may be rotated as rapidly as may be practicable, and thus a considerable increased speed in the manufacture of mouthpiece cigarettes may be obtained.

At the far side of the drum 6 there is a further guide 31 and beneath the lowest flute there is a filler support consisting of a thin fixed strip 32, whereby the continuous filler is supported in the flute. The guide 31 is not a tube but is of inverted U shape in cross section and the far end is flared laterally. As shown in Figure 2 the strip 32 is a wide strip but it is easy to see that the filler supporting part of the strip may be fairly narrow so that dust and shorts can fall away, the precise arrangement adopted depending on the degree to which the filler is compressed before it passes into the first guide tube.

As the drum rotates, the portion of the tobacco filler contained in the lowest flute, which is at that moment in alignment with the continuous tobacco filler, is severed therefrom since the two guides 5 and 31 are very close to the sides of the drum and movement of the latter causes the tobacco to be sheared. The ends of the guides adjacent the drum may if desired be formed as blocks of considerable area to assist in the shearing action and subsequent control of the sheared portion. The action is not pre-

cisely a cutting action but the sections are removed from the continuous tobacco filler leaving the filler portion ends sufficiently clean for the purpose in view. As the flute in alignment with the filler moves out of line therewith, the succeeding flute, which contains a stub portion as previously explained, is brought into that position and as the drum comes to rest the compressed leading end of the filler moves through the guide tube 5 and pushes the stub portion out of the flute and passes through the flute itself. As soon as the filler has moved the necessary distance the drum moves again, and the operation described is repeated.

The further guide 31 leads the filler portions and stub portions on to a paper web 33 on an endless band 34 which is the endless band or tape on which a continuous cigarette rod is made on continuous rod machines and which is hereafter referred to solely as a tape.

In this manner the cigarette paper web 33 which is carried on the rod forming tape 34 of the machine becomes loaded with alternate stub portions and filler portions and the rod forming tape carries them through the usual rod forming mechanism part of which is indicated at 35 where the paper is folded over, gummed and sealed and the resulting rod is thereafter cut into cigarettes each provided with a plug or other mouthpiece.

As soon as a flute containing a removed section of filler is clear of the continuous tobacco filler and its conveyor and other devices the removed section falls out of the flute, or may be positively removed, whereafter the flute is cleaned by an air blast from a nozzle 36 so that when it once more receives a stub portion there are no fragments of tobacco present which might later on become trapped between the stub portion and the cigarette paper wrapper. Moreover by passing the filler through the lowest flute of the drum any shorts are free to fall away past the filler support 32 which supports the filler in the flute if the support is made suitably narrow.

It is not always necessary to provide special mechanism for cleaning the flutes as the apparatus described can, on a suitable cigarette machine, be driven at a very high speed in which case the centrifugal force is sufficient to fling any particles of tobacco remaining in a flute clear of the drum.

The remaining details of the apparatus will be referred to in the following description of the driving devices. A sprocket wheel 37 Figures 3 and 7 is driven from any suitable part of the cigarette machine for example from the hopper driving mechanism, and drives a shaft 38. A bevel gear wheel 39 fixed on the shaft 38 drives another bevel gear wheel 40 on a shaft 41. The end of this shaft which is shown broken is used to drive other parts of the cigarette machine and is of no further interest. A gear wheel 42 is fixed on the shaft 41 and as shown in Figure 6 this wheel drives a further gear wheel 43 which drives a slightly larger gear wheel 44, these gear wheels 43 and 44 being also shown in Figure 3. The gear wheel 44 is mounted on a shaft 45 in a special manner as will be described later. A sprocket wheel 46 also mounted on the shaft 45 has a chain 47 on it which after passing over an idler sprocket wheel 48 drives a larger sprocket wheel 49 which is mounted on a shaft 50 and coupled thereto by an overload clutch 50.

This shaft 50 has fixed thereto a worm 51 which drives a wormwheel 52 fixed on a shaft 53 on which the aforesaid fluted feed wheel 11 is mounted. The crown cam 23 is also fixed on the shaft 50. A disc cam 54 fixed on the shaft 50 engages a roller 55 at the end of a cam lever 56 pivoted at 57. The lower end of the lever 56 is pivoted at 58 to a link 59 which is pivoted at 60 and 61 to levers 62 and 63 which are pivoted to a frame of the apparatus at 64 and 65. The free ends of these levers, as best seen in Figure 5, are pivoted to the reciprocating pusher 27. The return of the pusher is effected by a spring 66. Figure 1 and thus the stubs are fed towards the fluted drum 6 at the proper times.

At the end of the shaft 33 remote from the wormwheel 52 is a gear wheel 67. This drives a small gear wheel 68 to which is fixed a larger gear wheel 69. The latter drives a small gear wheel 70, and through this compound gear train a small roller 71, which is fluted or serrated as shown in Figure 2 and is driven to assist the passage of stock lengths into the flutes of the wheel 11, in the known manner.

On the shaft 38, Figures 3 and 7 there is also a small sprocket wheel 72. This is connected by a chain 73 to a similar sprocket wheel 74 fixed to a spindle 75 journalled in the frame of the apparatus as shown in Figure 3. At its ends this spindle has pulleys 76 and 77 fixed to it and from each pulley round belts 78 and 79 respectively drive grinding wheels for sharpening the knives 10.

The drive for one knife grinder 80 is clearly shown in Figure 2 where the belt 79 passes over idlers 81 and the other drive is identical. On the spindle 75 is also fixed a small sprocket wheel 82 which has a chain 83 on it passing round a further sprocket wheel 84. The latter is fixed on a spindle 85, journalled as shown in Figure 3 on which the rotary knives 10 are fixed.

The drum 6 is driven by a worm 86, the thread of which engages with a wormwheel 87 geared to the drum by gear wheels 88, 89 and 90, Figure 8, but the major portion of the worm is of zero lead, see Figure 2, so as the worm rotates, the drum moves while the helical part of the worm thread is engaging with the wormwheel and stops when the part of zero lead comes into engagement with the wormwheel.

The worm is driven from the gear wheel 44 but interposed between the gear wheel and its shaft 45, to which the worm is fixed is a clutch device which will now be described.

The hub of the gear wheel comprises a long sleeve 91 rotatable on the shaft 45 which is rotatably mounted in bearings as shown in Figure 2.

Part of the sleeve 91 forms a journal for a disc or wheel 92 whose rim is adapted to form part of a brake so that when a shoe is applied to the rim, the wheel is slightly checked in its rotation as will be more fully explained later. A convenient arrangement is, as illustrated, a V groove 93 in the rim of the wheel 92 and a brake shoe 94, Figure 1, of V section. The wheel 92 has a hub 95 on the periphery of which is a single ratchet tooth 96. Coaxial with this wheel is another wheel 97 whose rim is also of V section and a brake shoe 97, Figure 3, is also provided to engage this rim at times. The second wheel 97 is keyed to the shaft, see Figure 2, and thus is coupled to the drum 6.

On the second wheel 97 is a pivoted pawl 98

75

whose end is drawn into engagement by a spring 198 with a ring 99 which is keyed to the gear hub 91 and has a single ratchet tooth 100 on it. Thus when the gear 44 rotates and the pawl 98 is in engagement with the ring tooth 100, the wheel and the worm all rotate with the gear 44. The gear wheel has a quadrant shaped slot in it at 101 into which a pin 102, fixed in the neighbouring side of the first wheel 92, projects. Between said pin and another pin 103 on the gear wheel is a tension spring 104 which bends around the gear hub and tends to pull the first said pin around the quadrant slot. Normally, i. e. when apparatus is working, the rear end of the quadrant slot is in driving engagement with the pin 102.

The pawl 98 is wide enough to extend across the ring tooth 100 and the wheel tooth 96 and it is only when these two teeth are in alignment that the pawl can enter into driven engagement with the tooth-ring.

A device is provided for tripping the pawl when it is desired to stop the drum. For this purpose the pawl has a tail 105 and an abutment 106 fixed to a lever 107 can be moved thereby to intercept the tail as the second wheel 97 rotates, and disengage the pawl. The lever 107, as seen in Figure 1, also forms a stop for a bell crank lever 108 which carries the brake shoes 94 and 97 and is spring urged by a strong spring 109. When lever 107 is lifted to cause the abutment 106 to intercept the pawl tail, the lever 108 moves about its pivot and the shoe 107 engages the rim of wheel 97 slightly before the lever 107 has moved far enough for the pawl 98 to be tripped, so that the pawl is tripped while the brake is on and the second wheel is instantly arrested and thus the worm and the drum and intervening gears are all stopped.

As soon as the pawl is tripped the restraint exercised by the pawl tooth engaging with the wheel tooth 96 ceases and the first wheel 92 moves forward on the gear hub, 91 (i.e. it advances with respect to the gear) under the pull of the spring 104. Thereafter the gear wheel 44 and first wheel 92 continue to rotate together with the pin 102 in the forward end of the quadrant slot.

When it is desired to restart the drum, the lever 103 is moved in the reverse direction against the tension of the spring 109. This causes the brake shoe 94 to be applied to the first wheel 92 so that it is retarded and the spring 104 is stretched as the pin 102 moves backwards in the quadrant or driving slot. The lever movement simultaneously releases the brake shoe 107 on the second wheel 97 and permits the lever 107 to drop to the position shown in Figure 1 and the pawl 98 to pivot towards the position where it engages with the tooth 100. This engagement cannot take place until the tooth 96 on the first wheel is in alignment with the ring tooth 100 and at the instant of alignment the pawl springs in and all the parts move in time with the gear thus preserving the original timed relationship of the parts. As soon as the whole device is in operation again the pull on the lever 108 is relaxed and the shoe 94 is removed from its wheel. The pawl engaging abutment may be adjustable so that pawl tripping can take place at any desired position of the pawl as it rotates with its wheel.

A cigarette machine embodying the device is operated in the following manner. At the starting of the machine the clutch device just described is operated so that the drum is stationary.

When the tobacco filler is satisfactory and a wrapped rod can be formed and broken off in the customary manner, or even cut into cigarettes if desired, the clutch handle is operated to start the drum, and mouthpiece cigarettes are produced. When for any reason, it is desired to stop the machine the lever 107 is raised and the clutch handle 108 is urged by its spring 109 to stop the drum whereafter a continuous tobacco filler passes through the drum and the resulting wrapped rod can be broken off or cut up as desired. As soon as the drum stops, the machine may be stopped and such parts of the rod which have been made in the interval between the two movements removed from the normal produce of mouthpiece cigarettes.

Where the drum is fluted as in the present case, instead of being provided with bores, the stub portions can be moved axially much more easily into wide flutes than into small holes. Thus both actions are quicker than those in existing machines. The flutes are also easily cleaned by mechanical devices if necessary. Thus owing to the rapid method of feeding stub portions and discarding tobacco sections the drum can move at a very high speed which not only increases the output but has the further advantage that the forward movement of the continuous filler is scarcely impeded during the very short intervals during which the drum is still.

What I claim as my invention and desire to secure by Letters Patent is:

1. In apparatus for making mouthpiece cigarettes, the combination with a drum, and means supporting said drum for rotation on a fixed axis, said drum having the peripheral portion thereof formed to provide a series of axially directed flutes dimensioned to receive mouthpiece stubs, the width of the peripheral opening of each flute, measured circumferentially of the drum, being greater than the stub diameter, of driving means intermittently rotating said drum, means for inserting stubs into said flutes while said drum is stationary, and means spaced circumferentially of said drum from said last means for feeding a tobacco filler while said drum is stationary axially into and through a flute in which a stub has been inserted, whereby the filler moving into and through the flute carries the stub out of the flute, and stationary means co-

5 operating with said drum on rotation of the latter to shear off a section of the filler lying within the flute, the said rotation of the drum causing the sheared section to be replaced by the stub inserted in the next succeeding flute.

2. In apparatus for making mouthpiece cigarettes, the combination with a drum, and means supporting said drum for rotation on a fixed axis, said drum having the peripheral portion thereof formed to provide a series of axially directed flutes dimensioned to receive mouthpiece stubs, the width of the peripheral opening of each flute, measured circumferentially of the drum, being greater than the stub diameter, of driving means intermittently rotating said drum, means for inserting stubs into said flutes while said drum is stationary, and a stationary member located adjacent the lower portion of the drum, and spaced circumferentially of the drum from said last means, for feeding a tobacco filler while said drum is stationary axially into and through a flute in which a stub has been inserted, whereby the filler moving into and through the flute carries the stub out of the flute, stationary means cooperating with said drum on rotation of the latter to shear off the filler lying within the flute, the said rotation of the drum causing the sheared section to be replaced by the stub inserted in the next succeeding flute, and means positioned beneath said drum and dimensioned to bridge the peripheral opening of the flute into which the filler is fed, for supporting that portion of the filler which is being fed into and through a flute.

DESMOND WALTER MOLINS.
